ROOF CONSTRUCTION

Hal Callaway, Los Angeles, Calif.

Application May 22, 1933, Serial No. 672,138

8 Claims. (Cl. 108—26)

This invention relates to improvements in roof construction.

The general object of the invention is to provide a novel means for securing flashing members in position.

Another object of the invention is to provide a novel holding member for the upper end of flashing members.

A further object of the invention is to provide a novel anchor bolt for use with flashings in old roof constructions.

Other objects and the advantages of this invention will be apparent from the following description taken in connection with the accompanying drawing wherein:

Fig. 1 is a fragmentary section through a roof and roof parapet embodying the features of my invention;

Fig. 2 is a perspective view of my novel flashing anchor;

Fig. 3 is a fragmentary perspective view of my novel reglet strip;

Fig. 4 is a fragmentary perspective view of the flashing strip used;

Fig. 5 is a perspective view of my novel anchor bolt for use in old constructions; and,

Fig. 6 is a fragmentary section through a roof parapet showing the anchor bolt shown in Fig. 5 in an operative position.

Referring to the drawing by reference characters I have indicated a roof deck at 10 and its associated parapet at 12. As shown the parapet 12 is of the usual brick construction comprising a plurality of layers of bricks 13 adjacent the roof 10 having mortar joints 14 therebetween and other layers of brick 15 with a mortar joint 16 between the bricks 13 and 15.

In Fig. 2 I have shown a detail of my improved flashing anchor and indicated it generally at 17.

As shown the flashing anchor comprises a metal anchor piece 18, a bolt 19, and a metal clamping plate 20. The anchor piece 18 comprises a base portion 21 having at one end a downwardly extending flange 22 and at the opposite end an upwardly extending flange 23. The base 21 preferably tapers and has an aperture 24 therein.

The flange 23 includes a threaded aperture 25 to receive the threaded portion of the bolt 19.

The clamping plate 20 has an aperture 26 therein in which the bolt 19 is positioned and the upper and lower ends of the clamping plate are preferably arcuately bent to form engaging lips 27 and 28, respectively. The aperture 26 in the clamping plate 20 is preferably positioned nearer to the upper end thereof than the lower end.

In Fig. 3 I have shown a detail of my novel reglet strip and have indicated it generally at 30. As shown the reglet strip 30 comprises a strip of metal bent back upon itself to form a bottom portion 31 and a top portion 32 with a channelway 33 therebetween. The upper portion 32 includes an upturned flange 34 which is approximately flush with the end of the lower portion 31.

In Fig. 4 I have shown a detail of my novel flashing strip and have indicated it generally at 35. As shown the flashing strip is made of sheet metal and includes a face portion 36 having a right angularly bent flange 37 at the upper edge thereof. Adjacent the lower edge of the face portion I provide a slightly angular portion 38 which is bent in the same direction as the flange 37.

When constructing a building with which my invention is to be used a predetermined number of layers of the bricks 13 and 15 are laid and then a reglet strip 30 is positioned on the upper face of the bricks 13 adjacent the edge thereof which is nearest the roof. Then a plurality of anchor members 17 are placed in position in spaced relation. When placing an anchor member 17 in position the anchor piece 18 is placed with the base 21 thereof engaging the upper surface of a brick 13 and the flange 22 thereof engaging the side of the brick at the mortar joint 16 and with the bolt 19 extending towards the roof and the clamping plate 20 positioned adjacent the face of the brick 13 towards the roof. Thereafter the mortar joint 14 is formed over the reglet piece 30 so that the piece 30 becomes disposed in a reglet gash so that the reglet piece 30 and the anchor member 17 become embedded in the mortar. The other layers of the brick 13 are then laid.

When laying the roof covering such as composition roofing as indicated at 39, the sides thereof are bent upwardly along the parapet in the usual manner as at 40. The bolt 19 may be unscrewed a short distance to allow the flashing to be placed behind the plate 20 after which the flashing strip 35 is placed in position with the flange 37 thereof positioned in the channelway 33 of the reglet piece 30 and with the face portion 36 thereof extending downward over the bent portion 40 of the roofing material. The bolts 19 of the anchor member 17 are then tightened up thereby drawing the upper lip 27 into engagement with the bricks and the lower lip 28 into engagement with the face 36 of the flashing 35. Upon further tightening of the bolts 19 the lip 28 of the clamping plates moves the face 36 of the flashing strip into tight engagement with the portion 40 of the roofing material thereby clamping

the portion 40 tightly against the parapet. By providing the angular portion 38 on the flashing strip the lower end thereof tightly engages the portion 40 of the roofing material.

- 5 In Fig. 5 I have shown a detail of my novel anchor bolt and indicated it generally at 41. As shown the bolt 41 comprises a shank 42 having an enlarged rectangularly shaped head 43 integral therewith at one end and a threaded portion 44 adjacent the opposite end. The threaded end of the shank 42 is preferably slotted as indicated at 45. The head 43 is sharpened as indicated at 46 to provide diagonally opposed cutting points 47.

15 The anchor bolt 41 is adapted to be used in place of the anchor member 17 when replacing the roofing material of an old building. When using a bolt 41 an aperture 48 is drilled in the mortar joint 14 of a size sufficient to insert therethrough the head 43 of the bolt when the head is 20 turned with its length horizontal. The aperture 48 is drilled into the mortar joint 14 and through the mortar joint 16. The bolt 41 is then positioned in the aperture 48 with the head 43 thereof positioned in the mortar joint 16 and the threaded 25 end 44 projecting beyond the face of the bricks 13.

30 The flashing strip 35 is then placed in position with the flange 37 thereof positioned in the previously formed old reglet gash 49 and then a clamping plate 20 is positioned on the bolt and a nut 50 is positioned on the threaded portion 44 of the bolt. A suitable tool is then positioned in the bolt slot 45 and the bolt turned ninety (90) degrees. As the bolt is thus turned the head 43 thereof cuts into the mortar of the joint 16 to a 35 position wherein the length of the head is vertical in which position the head cannot be withdrawn through the aperture 48. Thereafter the nut 50 is tightened up against the clamping plate 20 which thereupon firmly clamps the flashing and roofing material to the parapet as previously 40 described.

45 From the foregoing description it will be apparent that I have provided a novel roofing construction which is simple in construction and highly efficient in use.

Having thus described my invention, I claim:

1. In a building including a roof deck and a parapet wall formed of a plurality of courses of layers of bricks having joints therebetween, a roofing material on said deck with the ends thereof bent upward against said parapet, a flashing member, a flashing anchor including a plate member and a clamping member, said plate member being embedded in the wall and comprising a base portion having a part engaging the wall and having a threaded aperture, said clamping member engaging said flashing member and a bolt positioned in said threaded aperture of said plate member and passing through said clamping member.

2. In a building including a roof deck and a parapet wall formed of a plurality of courses of layers of bricks having mortar joints therebetween, a roofing material on said deck with the ends thereof bent upward against said parapet, a flashing member including a portion arranged in one of said mortar joints and with a portion overlaying said upwardly bent portion of said roofing material, an anchor plate comprising a base portion having at one end a downwardly extending flange and at the other end an upwardly extending flange, said anchor plate being positioned on the layer and course of bricks adjacent to said flashing member with the base thereof engaging the top of said brick with the down-

wardly extending flange thereof engaging the face of said brick opposite said roof face and with said upturned flange towards said roof, a clamping plate having lip portions with one lip thereof 5 engaging said flashing member and the other lip engaging one of said bricks and means engaging said anchor plate and said clamping plate to firmly hold said clamping plate against said flashing member thereby clamping said upturned portion of said roofing material between said flashing member and said parapet.

3. In a building including a roof deck and a parapet wall formed of a plurality of courses of layers of bricks having mortar joints therebetween, a roofing material on said deck with the ends thereof bent upward against said parapet, a flashing member, said flashing member overlaying said upwardly bent portion of said roofing material, an anchor plate positioned on a brick of the course adjacent said roof and having a portion engaging the brick, a clamping plate having a portion engaging said flashing member and a portion engaging a brick, and fastening means engaging said anchor plate and firmly holding said clamping plate against said flashing member.

4. In a building including a roof deck and a parapet wall formed of a plurality of courses of layers of bricks having mortar joints therebetween, a roofing material on said deck with the ends thereof bent upward against said parapet, a flashing member, said flashing overlaying said upwardly bent portion of said roofing material, an anchor plate, said anchor plate secured in said wall, a clamping plate having lip portions at the top and bottom thereof and having an aperture therein adjacent the top thereof, said clamping plate extending downward with said lower lip thereof engaging said flashing member, said upper lip of said clamping member engaging one of said bricks, a bolt, said bolt engaging said anchor plate, and said aperture of said clamping plate and firmly holding said lower lip of said clamping plate against said flashing member thereby clamping said upturned portion of said roofing material between said flashing member and said parapet.

5. In a building including a roof deck and a parapet wall formed of a plurality of courses of layers of bricks having mortar joints therebetween, a roofing material on said deck with the ends thereof bent upward against said parapet, a flashing member, said flashing overlaying said upwardly bent portion of said roofing material, an anchor plate, said anchor plate being made of metal and comprising a base portion having at one end a downwardly extending flange and at the other end an upwardly extending flange, said upwardly extending flange having a threaded aperture therein, said anchor plate being positioned on a brick of the course adjacent said roof with the base of the plate engaging the top of the brick and with the downwardly extending flange thereof engaging the rear face of brick, a clamping plate engaging said flashing member and also engaging one of said bricks, and fastening means engaging said clamping plate and firmly holding said plate against said flashing member thereby clamping said upturned portion of said roofing material between said flashing member and said parapet.

6. In a building including a roof deck and a parapet wall formed of a plurality of courses of layers of bricks having joints therebetween, a roofing material on said deck with the ends thereof bent upward against said parapet, a reglet

member, said reglet member comprising a strip of metal bent back upon itself to form upper and lower portions having a channelway therebetween, said reglet member being positioned on 5 a layer of said bricks adjacent said roof and with its open face toward said roof and adjacent the roof edge of said bricks, a flashing member, said flashing member being formed of sheet metal and including a plane face having a right angularly bent flange at its upper edge and slightly bent portion adjacent its lower edge bent in the same direction as said flange, said flashing member being positioned with said flange in said channelway of said reglet member and with its plane 10 face overlaying said upwardly bent portion of said roofing material, a flashing anchor including a plate member and a clamping member, said plate member embedded in the wall adjacent said right member and being made of metal and comprising a base portion having at one end a downwardly extending flange and at the other end an upwardly extending flange, said upwardly extending flange having a threaded aperture therein, said clamping member being made of metal and having 15 lip portions at the top and bottom thereof arcuately bent in the same direction and having an aperture therein adjacent the top thereof, a bolt, said bolt being positioned in said threaded aperture of said plate member and passing through said aperture of said clamping member. 20

7. In a building including a roof deck and a parapet wall formed of a plurality of courses of layers of bricks having mortar joints therebetween, a roofing material on said deck with the 25 ends thereof bent upward against said parapet, a flashing member including a plane face having a right angularly bent flange at its upper edge and a slightly angularly bent portion adjacent its lower edge bent in the same direction as said flange, said flashing member being positioned with said flange in said channelway of said reglet member and with its plane face overlaying said upwardly bent portion of said roofing material, an anchor plate comprising a base portion having at one end a downwardly extending flange and at the other end an upwardly extending flange, said upwardly extending flange having a threaded aperture therein, said anchor plate being embedded in said wall adjacent said reglet member with said upturned flange towards said roof, a clamping plate having lip portions at the 30 top and bottom thereof arcuately bent in the same direction and having an aperture therein adjacent the top thereof, said clamping plate extending downward with said lower lip thereof engaging said flashing member, said upper lip of said clamping member engaging one of said bricks, a bolt, said bolt being positioned in said threaded aperture of said anchor plate and firmly holding said lower lip of said clamping plate against said flashing member thereby clamping said upturned portion of said roofing material between said flashing member and said parapet. 35

8. In a building including a roof deck and a parapet wall, a roofing material on said deck with the ends thereof bent upward against said parapet, a reglet member comprising a strip of metal bent back upon itself to form upper and lower portions having a channelway therebetween, said reglet member being embedded in said wall with its open face opening out of said wall towards said roof, a flashing member including a plane face having a right angularly bent flange at its upper edge and a slight angularly bent portion adjacent its lower edge bent in the same direction as said flange, said flashing member being positioned with said flange in said channelway of said reglet member and with its plane face overlaying said upwardly bent portion of said roofing material, an anchor plate comprising a base portion having at one end a downwardly extending flange and at the other end an upwardly extending flange, said upwardly extending flange having a threaded aperture therein, said anchor plate being embedded in said wall adjacent said reglet member with said upturned flange towards said roof, a clamping plate having lip portions at the top and bottom thereof arcuately bent in the same direction and having an aperture therein adjacent the top thereof, said clamping plate extending downward with said lower lip thereof engaging said flashing member, said upper lip of said clamping member engaging one of said bricks, a bolt, said bolt being positioned in said threaded aperture of said anchor plate and firmly holding said lower lip of said clamping plate against said flashing member thereby clamping said upturned portion of said roofing material between said flashing member and said parapet. 40
